UNITED STATES PATENT OFFICE.

H. H. POTTER, OF CARTHAGE, NEW YORK.

IMPROVED BURGLAR-ALARM.

Specification forming part of Letters Patent No. 56,262, dated July 10, 1866.

To all whom it may concern:

Be it known that I, H. H. POTTER, of Carthage, in the county of Jefferson and State of New York, have invented a new and Improved Burglar-Alarm; and I do hereby declare that the following is a full, clear, and exact description thereof, which will enable others skilled in the art to make and use the same, reference being had to the accompanying drawings, forming part of this specification.

The present invention consists in a novel and simple arrangement of mechanical devices for operating the hammer of the bell used in the burglar-alarm, as will be apparent from the following detail description thereof, reference being had to the accompanying plate of drawings, in which—

Figure 1 is a plan or top view of the operating devices; and Fig. 2, an elevation of the same, showing the bell in section.

Similar letters of reference indicate like parts.

A in the drawings represents the bed-plate of the alarm, having a center-post or standard, B, upon the upper end of which the bell C is screwed or otherwise properly secured; D, the bell-hammer, hung and turning by its stem E upon a fulcrum-pin, F, of the bed-plate, the tail end of which hammer-stem has a spiral spring, G, secured to it, that at its other end is secured to a fixed point or pin, H, on the bed-plate A.

I is a bent lever hung upon a fulcrum, J, of the bed-plate, to the tail end of which lever a spiral spring, K, is connected, that at the other end is hung to the pin H, hereinbefore

referred to. The bent lever I projects beyond the bell C, and by its curved arm L, which is provided with a series of teeth, a a, that, as the lever is swung toward the center-post B of the plate A, abut in turn against the arm b of the hammer-stem E, swinging it upon its fulcrum, and thus drawing the hammer back or tripping its stem, so that by the action of the spiral spring G it is thrown with great force against the bell, sounding the same, the number of sounds thus produced upon the bell being more or less, according to the length of movement given to the lever I and the number of its teeth or notches.

The plate A has a fixed upright, M, that is slotted in the direction of its length, by means of which the alarm can be set upon a fixed screw-head or other suitable pin in proper position for the lever I to be operated upon by the opening of a door or window, &c., and to thus cause the alarm-bell to be sounded or to be removed from such pin.

I claim as new and desire to secure by Letters Patent—

1. The bell C, or its equivalent, lever I, having toothed arm L, bell-hammer D, and springs G and K, when arranged and combined together substantially as described, and for the purpose specified.

2. The slotted upright M of the bed-plate A, as and for the purpose described.

H. H. POTTER.
